UNITED STATES PATENT OFFICE.

JOHN M. DAHLBURG, OF ATLANTIC, IOWA.

DOUBLETREE.

1,369,222.

Specification of Letters Patent. Patented Feb. 22, 1921.

Application filed May 18, 1917, Serial No. 169,488. Renewed July 23, 1920. Serial No. 398,542.

To all whom it may concern:

Be it known that I, JOHN M. DAHLBURG, a citizen of the United States, residing at Atlantic, in the county of Cass and State of Iowa, have invented certain new and useful Improvements in Doubletrees; and I do hereby declare the following to be a full, clear, and exact description of the invention, such as will enable others skilled in the art 10 to which it appertains to make and use the same.

This invention relates to improvements in a double-tree and has for one of its objects the provision of a device of this character, 15 whereby the double-tree will be held from tilting forward on the tongue, thus preventing wear of the tongue and other parts associated therewith.

Another object of this invention is the provision of a supporting structure secured to the tongue and adapted to pivotally support the double-tree upon the tongue and which will prevent the double-tree from tilting forwardly or rearwardly during use.

25 A further object of this invention is the provision of a pair of plates secured to the tongue and having their ends relatively spaced to receive a substantially U-shaped hanger carried by the double-tree, whereby 30 the double tree is pivotally supported on the tongue.

A still further object of this invention is the provision of a double-tree of the above stated character, which shall be simple, 35 durable and efficient, and which may be manufactured and sold at a comparatively low cost.

With these and other objects in view, as 40 will become more apparent as the description proceeds, the invention consists of certain novel features of construction, combination and arrangement of parts hereinafter more fully described and claimed.

For a complete understanding of my invention, reference is to be had to the following description and accompanying drawing, in which:

50 Figure 1 is a longitudinal sectional view of a double-tree constructed in accordance with my invention,

Fig. 2 is a fragmentary perspective view of the same.

Referring in detail to the drawing, the 55 numeral 1 indicates a tongue having the usual bow 2 secured to one end and to which

is adapted to be connected the vehicle. This tongue is especially adapted to be used in connection with light vehicles, such as buggies, carriages and the like, and the tongue has secured to its under face, a reinforcing 60 T-shaped strip 3, which has its T-shaped end secured to the under face of the bow 2 as illustrated at 4. The aforescribed structure relates to a well known construction of tongue and to which my invention is 65 applied.

A pair of relatively spaced plates 4 and 5 are secured to the upper face of the tongue 1 by the bolts 6, which secure the bracing strip 3 to the tongue. Upon one end of the 70 members 4 and 5 are horizontal head portions 7 formed which are bolted or otherwise secured to the upper face of the bow 2. The members 4 and 5 are bent to conform to the contour of the tongue, as clearly shown in 75 Fig. 1, and the member 4 adjacent its free end is bent upwardly and disposed in a plane above the tongue as illustrated at 8, and has its free end portion apertured to receive the bolt 9. The member 5 is increased 80 in width as shown at 10 and has formed thereon, downwardly depending lips 11, which engage the side faces of the tongue for strengthening the tongue and aiding in securing the member 5 to the tongue. The 85 member 5 at its increased portion in width as shown at 10 is bent at right angles to form a vertically disposed supporting member 12, which has its upper end bent at right angles as illustrated at 13 for supporting the 90 portion 8 of the member 4. A downwardly and forwardly extending extension 14 is formed upon the right angled end 13 of the supporting member 12 and is spaced from the portion 8 of the member 4 to receive a 95 substantially U-shaped hanger 15, which is apertured to receive the bolt 9. The bolt 9 is threaded to the downwardly and forwardly extending extension 14, whereby the hanger 15 is pivotally connected between the members 4 and 5. The substantially U-shaped hanger 15 is bolted or otherwise secured to a double-tree 16 as 100 illustrated at 17. The double-tree 16 is of the usual construction and has pivotally secured to each end, the swing trees 17 to which the draft animals are hitched.

The substantially U-shaped hanger 15 being pivotally secured to the members 4 and 5 supports the double-tree 16 over the upper 110

face of the tongue and will prevent the double-tree from tilting forwardly and rearwardly during use.

From the foregoing description taken in connection with the accompanying drawing, it will be noted that the necessity of making a hole in the tongue for securing the double-tree 16 thereto, is obviated, and it also may be noted that the device may be readily 10 and conveniently applied to the tongue now in use.

While I have shown and described the preferred embodiment of my invention, it will be understood that minor changes in 15 construction, combination and arrangement of parts may be made without departing from the spirit and scope of the invention as claimed.

Having thus described my invention, what 20 I claim is:

A wagon tongue attachment comprising upper and lower plates secured one above the other to the top face of the tongue and extending rearwardly from the double tree 25 of the tongue to the bow, means connecting

the rear ends of the plates to the bow, said upper plate having its forward portion inclined upwardly and having its forward end disposed in a plane above the tongue and parallel therewith, said lower plate having 30 its forward portion bent vertically and horizontally, and the horizontal portion disposed against the forward portion of the upper plate to support the same and limit its downward movement, an angularly related 35 extension formed on the horizontal portion of the lower plate and spaced from the free end of the upper plate and the tongue, and a clamp pivoted between the free end of the upper plate and the extension and secured 40 to the double-tree so that said double-tree is located between the extension and the tongue for free pivotal movement.

In testimony whereof I affix my signature in presence of two witnesses.

JOHN M. DAHLBURG.
